[57] CLAIM

The ornamental design for an insulated pitcher or the like, substantially as shown and described.

DESCRIPTION

FIG. 1 is a front and side perspective view of an insulated pitcher or the like, showing my new design;
FIG. 2 is a rear elevational view thereof;
FIG. 3 is a front elevational view thereof;
FIG. 4 is a side elevational view thereof, the other side being a mirror-image;
FIG. 5 is a top plan view thereof, the bottom of the insulated pitcher or the like being unornamented.
